UNITED STATES PATENT OFFICE.

CLAUDE R. HOZIOR, OF RICHMOND, VIRGINIA.

GUARD FOR TROWELS.

No. 926,567.

Specification of Letters Patent. Patented June 29, 1909.

Application filed December 30, 1908. Serial No. 470,057.

To all whom it may concern:

Be it known that I, CLAUDE R. HOZIOR, a citizen of the United States, residing at Richmond, in the county of Henrico and State of Virginia, have invented new and useful Improvements in Guards for Trowels, of which the following is a specification.

This invention relates to trowels, and the object of the invention is to provide a simple and effective guard positioned upon the shank of a trowel directly between the handle and the blade of the trowel whereby the mortar received upon the blade of the trowel is prevented from contacting with the hand of the mason using the trowel.

With the above, and other objects in view which will appear as the description progresses the invention resides in the novel construction of guards for trowels hereinafter fully described and claimed.

In the drawing, Figure 1 is a perspective view of an ordinary trowel provided with the improved guard. Fig. 2 is a transverse sectional view through the shank of the trowel and looking toward the guard. Fig. 3 is a vertical sectional view upon the line 3—3 of Fig. 2.

In the accompanying drawing the numeral 1 designates a trowel of the ordinary construction, and comprising a blade 2, shank 3 and handle 4^a. The handle 4^a is provided with the usual ferrule 5 whereby it is effectively retained upon the offset shank 3 of the trowel.

The numeral 4 designates the improved finger guard. This guard 4 is constructed of a single strip of flat material, preferably steel or iron and is provided with a suitable opening 5 of a size corresponding with that of the offset portion of the shank 3, and the guard 4 is also provided with a rearwardly extending ferrule 6 which is of a size adapted to fit snugly over the ferrule 5 of the handle 4^a. The top portion of the flattened guard 4 is provided with a central depression 7 which is adapted for the reception of the thumb or fore finger of the artisan manipulating the trowel. This cut away portion or depression 7 is of an especial usefulness when the

trowel is being employed for pointing up the mortar joints between stones or bricks of buildings.

From the above description taken in connection with the accompanying drawing it will be noted that I have provided an extremely simple and effective mortar guard for trowels, one which may be easily and quickly positioned upon the ferrule of the handle of any ordinary trowel by simply removing the handle from the shank of the trowel and inserting the thimble of the guard upon the trowel, one which effectively prevents the mortar carried by the trowel from contacting the hand of the artisan, and one which has its upper edge provided with a depression adapted for the reception of the thumb or fore finger of the artisan so that the mechanic may retain a firm grip upon the trowel while pointing up the joints of mortar between the bricks or stones of a building.

Having thus fully described the invention what is claimed as new is:

1. The combination with a trowel comprising a blade having an offset shank and a handle provided with a ferrule connected with the shank, of a guard comprising a flattened member having a thimble adapted to engage the ferrule of the handle and an opening communicating with the interior of the thimble adapted to engage the shank of the trowel.

2. The combination with a trowel comprising a blade, an offset shank, and a handle provided with a ferrule connecting the offset shank, of a flattened guard provided with an orifice and a thimble, the thimble engaging the ferrule of the handle and the opening adapted for the reception of the shank of the trowel, and said guard having one of its edges provided with a centrally arranged depression, substantially as and for the purpose set forth.

In testimony whereof I affix my signature in presence of two witnesses.

CLAUDE R. HOZIOR.
